UNITED STATES PATENT OFFICE.

DAVID C. ROGERS, OF GREENFIELD, MASSACHUSETTS.

MITERING-MACHINE.

SPECIFICATION forming part of Letters Patent No. 272,903, dated February 27, 1883.

Application filed November 3, 1882. (No model.)

To all whom it may concern:

Be it known that I, DAVID C. ROGERS, a citizen of the United States, residing at Greenfield, in the county of Franklin and Commonwealth of Massachusetts, have invented a new and useful Improvement in Miter-Boxes, of which the following is a full and true specification.

The accompanying drawings show the invention, and form a part of this specification, in which—

Figure 1 shows a plan view of the machine, Fig. 2 a transverse section of same.

A is the bed-plate of the machine; B, the back against which the material to be mitered, usually rests; C, the swinging lever, having on it iron posts, through which the saw passes, and which is adjustable horizontally, so as to be set at any angle with the back, up to forty-five degrees. D is an adjustable arm or rest to hold the work when it is desired to cut at an angle larger than forty-five degrees, or to cut a miter on segmental work.

In the miter-box which I patented (No. 220,732) the wood to be sawed is placed against the back B, the saw in the posts or standards on the adjustable lever pivoted at the rear is swung around, enabling any cut to be made, from an angle of forty-five degrees down to a right line; but no stick can be cut at a larger angle than that, because the lever can never be swung around to more than that extent.

In various uses in carpentry and other wood-work—cutting moldings, stair-rails, frames, &c.—it is often desirable to cut the work at a longer angle than the miter-boxes admit as at present constructed. It is also very important to cut circular or segmental work for frames, patterns, &c., at different angles, which cannot be done on a common miter-box with any safety or ease. I accomplish this by my invention, which consists of a rest, D, attached to a segmental arm, E, which runs through the back B, and is supported by an arm or bracket, F, projecting from the back, and slotted to hold and guide the segmental arm E.

This arm E is also slotted vertically, and through it passes a set-screw, O, into the bracket F, which holds it at any desired point. In the back B is a recess, into which the rest D sits flush with the face of the back when withdrawn and not in present use.

The operation of my device is as follows: If it is desired to cut a piece of work at an angle larger than forty-five degrees, it is laid up on the table; but instead of placing it against the back of the machine the adjustable sliding rest is shoved out till the desired angle is made with the saw, when it is secured with the set-screw behind. The angles at which the material can be cut may be varied indefinitely by swinging the adjustable lever, and also by extending it lengthwise.

Circular or oval work, which now can be only cut with difficulty in the machines as at present made, having no fixed support except at the point of the curve, where, when it is to be cut, is in my machine supported firmly by the sliding rest, which holds it at any point of the curve to which it is adjustable by turning the set-screw in the rear. This, it will be perceived, is a decided advantage over machines as now made.

What I claim as my invention, and desire to secure by Letters Patent, is—

1. In a miter-sawing machine, the combination, with the bed-plate A, having a back recessed for the reception of a rest, D, and swinging lever C, of the segmental adjustable rest D, composed of parts D E, as and for the purpose set forth.

2. In a miter-box, the auxiliary rest composed of upright portion D and a horizontal segmental slotted arm, in combination with the bed-plate, provided with an upright fixed back and a suitable fixed lug and a suitable clamping-screw, substantially as and for the purpose set forth.

DAVID C. ROGERS.
